United States Patent Office

Des. 184,717
Patented Mar. 31, 1959

184,717

NARROW LACE OR SIMILAR ARTICLE

Rene Duplaise, Coventry, R.I.

Application August 25, 1958, Serial No. 52,362

Term of patent 3½ years

(Cl. D47—6)

The figure is a top plan view of a narrow lace or similar article, showing my new design which is repeated in the horizontal direction.

I claim:

The ornamental design for a narrow lace or similar article, substantially as shown.
